WRITING MACHINE

William E. McFarland, Nutley, N. J.

Application September 28, 1943, Serial No. 504,092

14 Claims. (Cl. 197—126)

This invention relates to novel mechanism incorporated in, or attached to, front-strike typewriters and similar front-strike writing machines, for accomplishing convenient front feeding of writing sheets, which I shall call work-sheets, around the cylindrical platen and into the machine, as contrasted with the more usual method of feeding work-sheets into the machine from in back of the cylindrical platen. The front-feed method of inserting work-sheets requires that the work-sheets be backed in the machine by rotating the platen oppositely to the normal line-spacing direction. The usual ribbon-vibrator and holder, ribbon-guard, and other devices that are necessarily closely adjacent the front portion of the platen in front-strike writing machines, largely prevent the use of a fixed front paper-table for front introduction of work-sheets, necessitating a suitable arrangement.

My invention is particularly adapted to be used in typewriting applications where it may be desired to retain the carbon copy work-sheets in the typewriter, while inserting and removing a number of individual original work-sheets; likewise adapted to the condition where continuous work-sheets are used for some of the copies, and an individual original work-sheet is to be used for each original copy written; and is adapted to meet various requirements where front feed is desired.

An object of my invention is to provide a novel and neatly installable mechanism for front-strike writing machines, which permits work-sheets to be introduced at the front of the platen, to be backed to writing position.

Another object of my invention is to provide a flexible feeding-sheet for front-strike writing machines, which can conveniently be advanced to operative position to function as a paper-table, which will lead the inserted end of work-sheets to full engagement with the usual feed rollers under the platen.

Another object of my invention is to provide a flexible feeding-sheet for front-strike typewriters, which in inoperative position is disposed in back of the platen, disengaged from the grip of the feed rollers against the platen, but engageable to be gripped by the feed rollers and advanced by platen rotation to useful position.

Another object of my invention is to provide for storing a feeding-sheet in inoperative position underneath the usual inclined paper-table, so that the feeding-sheet is distinctly separated from the work-sheets, and is fully out of the way and out of sight.

Another object of my invention is to provide for easy replacement of the feeding-sheet.

Another object of my invention is to provide a feeding-sheet of particular design and shape, and with openings in the sheet so spaced as to register over the areas of pressure produced by the engagement of the feed rollers against the platen.

Another object of my invention is to provide for advancing a flexible feeding-sheet from a storage position, to useful front-feeding position, by rotation of the platen in line-space direction, with means to prevent the feeding-sheet from advancing beyond the position where openings provided in the sheet are registered over the feed rollers, and with means provided to automatically return the feeding-sheet to storage position when the platen is rotated in counter-line-spacing direction.

Other objects and advantages of my invention will be apparent from the following description.

Referring to the drawings, my invention is illustrated as incorporated in a well known kind of front-strike typewriting machine, and a manifolding mechanism, to operate carbon ribbons, of the same general kind as disclosed in my Patent No. 2,202,958, is included with the machine. My present invention is equally adaptable to be used where manifolding is done by means of sheet carbon, and the design and method of operation would be the same; however some of its advantages can best be illustrated in combination with the use of carbon ribbons for manifolding means.

Figure 1 is a top plan view, of a front-strike typewriter embodying my invention, with the keyboard and certain other parts omitted, and illustrates the feeding-sheet as disposed in the inoperative, or storage, position.

Figure 2 is an end view of the rear portion of the carriage, the dotted lines showing the relative position of the platen, and of the special under-table which supports the feeding-sheet.

Figure 3 is a cross-sectional view, taken on line III—III of Figure 1, showing the arrangement that provides a compartment, or chute, under the regular paper-table.

Figure 4 is a top plan view, showing portions of the carriage, and illustrates the feeding-sheet as having been advanced to position for leading in a work-sheet, and shows the openings in the feeding-sheet as registered over the feed rollers. Figure 4 shows the paper-bail as having been swung to open, or extended, position, away from the platen, to facilitate more convenient use of the feeding-sheet.

Figure 5 is a view of the feeding-sheet as re-

moved from the machine, including the clip to which a cord is fastened.

Figure 6 is a cross-section of the feeding-sheet, taken on line VI—VI of Figure 5, and illustrates the sealed fold-over which enables quick attachment of the clip to the feeding-sheet.

Figure 7 is a front elevation of a portion of the carriage, showing the feeding-sheet in operative position, and showing three separate work-sheets as having been properly placed for front feeding.

Figure 8 is an enlarged view of the parts comprising the spring-spool assembly, which provides a yielding pull on the feeding-sheet at all times.

Figure 9 is an enlarged perspective view of the complete front-feeding device, as removed from the machine, with portions broken away.

Figure 10 is a diagram, taken as a cross-section on line X—X of Figure 1, showing certain parts of a front-strike typewriter embodying my invention, and illustrating the feeding-sheet as being withdrawn to storage position.

Figure 11 is a diagram, similar to Figure 10, but showing the condition when the fingerpiece is being actuated to press the feeding-sheet into engagement for feeding.

Figure 12 is a diagram, similar to Figure 11, but showing the condition when the feeding-sheet has been fully advanced. Figure 12 shows a roll of continuous paper as providing the work-sheet for receiving the impressions of the carbon paper ribbon. Figure 12 also shows an individual work-sheet as having been introduced between the projecting portion of the feeding-sheet and the platen, in front-feed manner.

Figure 13 is a diagram, similar to Figure 12, but showing the condition after the platen has been turned backward to complete the front-feed operation.

Figure 14 is a diagram, similar to Figure 10, but illustrating a modification of my invention, in which no separate compartment is provided to shield the feeding-sheet.

The construction of front-strike typewriters of the general nature of using a cylindrical platen to feed work-sheets, is well known and will not be described here, and the typewriter shown in the drawings is described only to the extent of identifying the parts which have a relationship to my invention. The particular typewriter shown is that commonly known kind of machine having a main frame on which is mounted a letter-spacing carriage. Since my invention is directed to the carriage, the main frame and parts mounted thereon are in general omitted from the drawings.

In Figure 1, the main frame of the machine is indicated by the letter "A." The carbon paper ribbon spool-storage and tensioning unit is merely identified as a unit by the letter "B." The carbon ribbon feeding unit, which is driven in feeding steps by operation of the line-space lever, is likewise indicated by the letter "C." The single or multiple carbon ribbons obviously extend from unit B to unit C along the length of the carriage and platen, in register with the writing line of the machine.

The typewriter as illustrated includes right-hand and left-hand carriage end castings 1 and 2 respectively, which provide firm support for various longitudinal members (not shown) of the carriage. The rotatable platen 3 is journaled in the castings 1 and 2. Slideable clips 4, are

mounted on the end castings 1 and 2, to permit easy removal of the platen 3. The platen extension-shaft, 5, connects the platen with the manually operated platen-turning knob 6. A line-space ratchet 7, is provided at the left end of the platen 3, and a ratchet-roller assembly 8 bears against the teeth of the ratchet 7. A line-spacing lever 9, is ordinarily used to return the carriage to position to start each new line of writing, and is connected to the unit C to gradually advance the carbon paper ribbons as new lines are written. The assembly of parts, 10, provide for linking the lever 9 to engage against the ratchet 7 to produce a line-space of the work-sheets each time the lever 9 is fully actuated. The fingerpiece 11, near the right-hand end of the carriage, operates the automatic margin-setting devices of the machine, the details of which are not shown.

A series of feed rollers 12, are normally spring-pressed to engagement with the platen 3, along a forward under portion of the platen and provide for gripping a work-sheet. The feed rollers 12 rotate freely as the platen 3 is turned in either direction of rotation. Another series of feed rollers, 13, is engaged along a rear portion of the platen, at a position also slightly under the platen. The details of applying spring pressure to the rollers 12 and 13 is not shown. While I have illustrated each of the rollers 12 and 13 as being an individual roller, there is no objection to the use of a single, much longer, roller to replace each series. It is however, better, that if long feed rollers are used, that there be several areas of the roller with full circumference and several areas of lesser circumference so as to provide a number of relatively small pressure areas against the platen. This is because the feeding-sheet has a number of openings, preferably one for each pressure area, and it is desired that these openings need not be large in size.

A shaft 14 provides for rotatably mounting the feed rollers 12, while the shaft for mounting the rollers 13 is not illustrated. A paper-deflector pan, 15, extends along the under portion of the platen, and is curved to approximately the radius of the platen, but it is separated slightly from the platen at all times to permit free movement of work-sheets, without binding. A paper-release lever 16, is located near the left-hand end of the carriage, and is actuatable to cast off the feed rollers 12 and 13. When the rollers 12 and 13 are cast off, there is no gripping engagement between the feed rollers and the platen, and a work-sheet may then slide freely without rotating the platen. A carriage-release lever 17 is located near the lever 16, and is used to disengage the letter-spacing mechanism of the carriage when this is desired.

A paper-bail cross-member 20, consists of a bar of metal of approximately the length of the platen, and having a knife-like edge to enable accurate tearing of work-sheets from a continuous roll. The cross-member 20 has side arms at the right and left ends, in which small bearing pins 21 are fixed, and the pins 21 extend into brackets 21 and 22, the bracket 21 being fastened to the left-hand casting 2, and the bracket 22 being fastened to the right-hand casting 1. The cross-member 20 provides a paper-bail of the well known "front-pivoted" class of bails. The cross-member is normally located close to the platen 3, to press work-sheets to the curvature of the platen, but it may be dis-

posed in an open, or extended, position as shown in Figures 4 and 12.

An inked ribbon 31, extends between a pair of identical spools 30, and is fed from one spool 30 to the other, through a ribbon-vibrator 32. The ribbon-vibrator 32 is located close to the platen 3, and each time a typebar swings to printing position, the vibrator 32 raises the ribbon 31 in the well known manner. A type-guide 33, is located closely adjacent the ribbon-vibrator 32, and serves to correctly align the types as they meet the ribbon 31 for printing on a work-sheet. The typebars 34 are arranged in the usual well known manner, and are actuated by the typing keys (not shown). A shield 35, is located between the ribbon 31 and the platen 3, and its location is slightly to the rear of the type-guide 33. The shield 35 guards the leading ends of work-sheets, as they feed around the platen from the rear, from fouling with the inked ribbon 31. A portion of the shield 35 extends above the position of the ribbon 31. The spools 30, ribbon 31, vibrator 32, guide 33, and shield 35 are all mounted on the main frame of the machine, and several of these parts are necessarily close to the platen. This, together with the fact that the types must strike the platen along the whole length of the writing line, prevents the providing of a satisfactory fixed paper-table for introducing work-sheets at the front of the platen. Without the benefit of a front-feed device, such as my invention, it is difficult and inconvenient to so introduce a work-sheet in a front-strike typewriter that it can be engaged by the front feed rollers 12.

A shell 38, made of sheet metal, encloses various working parts of the rear portion of the carriage, such as the tabulator devices, margin-setting devices and other parts, none of which are shown in the drawings.

A fixed paper-table 40, is made of formed sheet metal, and is attached to the carriage by means of screws 41, which thread into rigid brackets (not shown). It is obvious that the paper-table 40 assists the shell 38 in the matter of enclosing various working parts of the carriage, but the important functions of the table 40 are to direct the leading ends of rear-fed work-sheets to feeding engagement with the platen, and to support such portions of work-sheets as extend toward the rear of the machine. The table 40 has a forward edge which is parallel with the platen, a slight distance away from the rear-most portion of the platen, and a slight distance above the rear feed rollers 13. From this forward edge, the main surface of the table 40 inclines rearwardly upward, the inclined surface being suitable for supporting work-sheets in the usual well known manner. As is usual in front-strike typewriters, any work-sheet that is inserted at the front of the platen, and ejected at the rear of the platen by turning the platen backward, will be deflected up and over the paper-table. The relative placement of the table 40, the platen 3, the rear feed rollers 13, and the pan 15 can be clearly seen in Figure 10. The pan 15 is not an essential element in the initial process of gripping a work-sheet between the feed rollers 13 and the platen 3, but is necessary to guide the leading ends of work-sheets from one set of feed rollers to the other set.

Another piece of formed sheet metal 42, is located underneath the paper-table 40, and this may be termed the under-table since its functions are somewhat similar to those of a paper-table. The under-table 42 has a main area that is

5 directly under the paper-table 40, and at the sides of this main portion are side portions which are bent at right angles to the main portion, to form side walls of a chute or compartment. Another right angle bend of the side portions provides a surface enabling the under-table to be soldered or brazed to the under side of the table 40. The upper rear portion of the table 42 is curved, which is of assistance in reducing the 10 size and bulk of the shell 38. The upper rear portion of the table 42 is also much narrower than the main body of the table. As shown in the drawings, the two tables 40 and 42, as united in a unit, provide a space in the nature of a chute, or compartment, for storage of the feeding-sheet which will be described. The several parts which 15 control the engagement of the feeding-sheet are mounted directly on the under-table 42, and therefore all parts of the front-feeding device, including the usual paper-table, are assembled 20 in a unit. Like the table 40, the under-table 42 has a forward edge, which is parallel with the platen, and this forward edge is spaced a slight distance below the edge of table 40, and also a slight distance to the rear. The forward edge of table 42 is also close to, and slightly above, the series of feed rollers 13. A curvature is provided in the lower forward portion of the main surface of the table 42, which is of assistance in feeding the feeding-sheet in and out of the compartment without excessive friction.

25 A modified form of paper-table, 43, is shown only in Figure 14. The single modified table 43 serves the purposes of both tables shown in the other drawings. In the modified design, no chute is provided, the feeding-sheet being supported directly on the surface of the main table. When using the modified design, the accessories which 30 are to be described would be attached directly to the table 43.

35 A bracket 44, is soldered to the under surface of the right-hand portion of table 42, and the free end of the bracket has a drilled hole to provide a bearing for the control rod to be described. A 40 similar bracket 45, is likewise affixed to the left-hand portion of the table 42, and includes an up-standing extension with a drilled hole to accommodate the end of a spring.

45 A round rod, 46, is mounted on the table 42 by means of the brackets 44 and 45, in a manner whereby the rod may be rotated in a partial revolution. The location of the bearing holes in the brackets 44 and 45 is such that the axis of the rod 46 is well below the rearmost portion of the table 42. The rod 46 has a center portion 50 of the shape of a broad inverted U, including two upright sections 47. At the left-hand end of the rod 46 is a bent-up portion, having a small opening at its end to receive the end of a small spring. 55 At the right-hand end of the rod 46 is a bent-up portion, terminating in a loop 49 which serves as a fingerpiece. While the pivotal axis of the rod 46 is located well underneath the rear portion of the table 42, the center section of the rod, between the uprights 47, crosses above the narrow rear portion of the table 42, as clearly shown in 60 Figure 9.

65 A projecting piece 48, extends toward the right from the extreme rear portion of the table 42, and provides a stop for the right-hand upright 47. The rod 46 can have only a limited partial rotation, as the upright 47 will strike the stop 48 when it moves in one direction and will strike the main body of the table 42 in the other direction. 70 The fingerpiece 49 extends through an opening

in the shell 38, and is located at the right-hand end of the carriage for convenient right-hand operation on the part of the typist while operating the platen-turning knob 6 with the left hand, as both operations are done simultaneously. A small coil spring 50, is attached at one end to the rod 45, and at the other end to the bracket 45, urging the rod 45 to one limit of movement where one upright 47 is bearing against the stop 48.

A flexible cord 51, of catgut or other suitable material, is fastened at one end to a thin metal strap 52, which serves to provide a clip to fasten the feeding-sheet to the machine, the screw 53 holding the cord fast to the clip 52. The opposite end of the cord 51 is fastened to a spool 54, by means of a screw 58. A bracket 59 is affixed to the under side of the rearmost portion of the table 42. A round shaft 55, is firmly attached to the bracket 59 by means of a lock nut 56. The spool 54 may rotate on the shaft 55. The shaft 55 has a slot in its left end, and a coiled spring 57 is anchored to the shaft by means of the slot, and is fastened at its opposite end to the spool 54 by means of a pin extending from the spool. By means of the spring 57, the spool 54 is constantly tensioned and exerting a yielding pull on the cord 51, tending to wind the cord about the spool. A second lock nut 56 is threaded on the left end of the shaft 55 to retain the spring 57 in position.

The front-feeding-sheet 60, the details of which are clearly shown in Figures 5 and 6, is made of a sheet of paper or of a similarly flexible material. If made of paper, it should be of a grade to stand repeated use. It must be sufficiently flexible that it may be fed around the platen in the manner of a work-sheet. The width of the feeding-sheet 60 is just slightly narrower than the width of the under-table 42, so that the sheet 60 will slide freely in the chute between the tables 40 and 42. The width of the chute, and likewise the width of the sheet 60, should be at least approximately as wide as the width of the widest work-sheets that are to be front-fed into the typewriter.

Two fold-overs 61 are provided at the upper portion of the feeding-sheet, one to each side of center. The fold-overs are sealed with mucilage or otherwise, along their edges, leaving a space similar to a hem on each side of the center, into which the clip 52 can easily be fitted, by inserting one end of the clip 52 in one of the fold-overs, sliding it well to one side of center, and then inserting the remaining end of the clip in the other fold-over. The clip 52 can likewise be easily removed to replace a worn-out feeding-sheet. The feeding-sheet 60 is so designed that the leading end is in the form of a very blunt point.

Openings 62 and 63 are provided in the feeding-sheet 60, and are of such size and so spaced, that when the feeding-sheet is in its operative position as shown in Figure 4, the openings are registered over the areas of pressure produced between the feed rollers 12 and 13 and the platen 3. The lower portions of all these openings 62 and 63 are pointed in the direction of the leading end of the feeding sheet, which tends to prevent the edges of the openings from jamming against the forward edge of the paper table 40, during the operation of transferring the feeding-sheet to storage position in the compartment.

When the feeding-sheet has been attached to

the machine, by means of the clip 52, the cord 51 is obviously pulling on the sheet and this will maintain the sheet 60 at its maximum retracted position on the table 42, with the top edge of the sheet, reinforced by the clip 52, bearing against the uprights 47 of the control rod.

The carbon paper ribbons 70, extend from a storage-spool located in the unit B at the right-hand end of the carriage, along the front portion of the platen and in register with the writing line, to the feeding unit C, from which worn-out portions of the ribbons are rejected as the typewriter is operated.

A sheet of continuous paper 75, feeds from a roll and is used to produce a carbon copy of the typewritten matter. A number of such rolls, or a multi-ply roll, may be used where more than one continuous sheet is desired. Small individual work-sheets 76 and 77, are shown in Figure 7, as used for a first carbon copy and a second carbon copy, and the sheet 76 is shown also in Figure 14 in dotted lines. The sheet 78 is shown in several of the drawings, and is the original work-sheet to receive imprints directly from the prime inked ribbon 31.

The manner in which the work-sheets are led to feeding engagement with the platen may easily be illustrated by placing a sheet of writing-paper in a front-strike typewriting machine, in such a position that the sheet is placed to receive a line of typing approximately an inch below the extreme top edge of the sheet. Thus, an end of this writing sheet will protrude moderately above the writing line and slightly above the usual ribbon-shield that is a part of most typewriters. This protruding end may now be used for the purpose of a paper-table, to introduce the bottom end of a work-sheet, or pack of work-sheets, between the first-mentioned sheet and the platen, and if the platen is now rotated backward, with respect to the usual line-space direction, by means of the usual platen-turning knob, the work-sheet or pack will be fed backward around the platen, the first-mentioned sheet serving to lead the ends of the work-sheets to engagement with the feed rollers and platen. At the very beginning of platen rotation the work-sheets are fed by friction only, but are efficiently drawn to the position of actual gripped engagement.

As the platen is rotated backward to a further degree, the first-mentioned sheet, which was used as a feeding-sheet, will be ejected from the grip of all the feed rollers at the rear of the platen, and the bottom ends of the work-sheet or pack of sheets will be supported on the paper-table at the rear of the platen. Without the benefit of the expedient just described, it is very difficult to introduce a work-sheet at the front of the platen, because of the interference of such necessary parts as the ribbon-vibrator, type-guide, and ribbon-shield, and since no fixed paper-table is provided in front-strike typewriters.

The simple expedient just described is frequently used by typists for "front feeding" small typing pieces such as envelopes, cards, etc. and is advantageous in that it provides a very positive method of leading stiff materials to full engagement with the platen; however this expedient is useful in only a limited manner, whereas my invention provides a fully efficient and versatile method of introducing work-sheets at the front of the platen. In many cases where front feed is wanted, it is desired that certain work-sheets remain in the typewriter, while a number of separate original work-sheets are inserted and with-

drawn from the typewriter. The work-sheets which provide the carbon copies can often be continuous sheets, either to accumulate a register on one long sheet, or to be cut off into individual copy sheets by means of a paper-bail having a knife-edge. A particular reason for using "front feed" in such cases is that there is then no necessity to remove the continuous paper from the typewriter each time a new original work-sheet is superposed.

In the usual front-feeding application, where perhaps continuous paper is used for the carbon copies, it is generally desired that after one original sheet has been typed and removed, that the continuous paper be advanced a distance, then the next original work-sheet positioned in front of the continuous sheet and in proper registration with it, so that when the platen is turned backward, all sheets of the writing pack are in position for writing the first line.

As shown in Figures 1, 10 and 13, the feeding-sheet when stored, is located in the chute that the tables 40 and 42 provide. In this position, the feeding-sheet is completely out of the way and does not interfere with either the appearance, or the general operation, of the typewriter. There is obviously a gap between the lower forward edges of the tables 40 and 42, and this gap is the full width of the under-table 42, but work-sheets that are turned backward in the machine by means of the platen-turning knob 6 do not enter through this gap into the storage compartment, and such backward-turned work-sheets are deflected up and over the table 40 by the table 40.

There is an opening, the full width of the feeding-sheet, between the upper rear edge of the paper-table 40, and an edge of the carriage shell 33 that is parallel with the edge of table 40 but spaced an inch or so toward the rear from the table 40, and this opening is best shown in Figure 4. A portion of the under-table 42, as well as the feeding-sheet and some other parts, is visible through this opening. This opening provides access to the feeding-sheet to allow quick replacement. In practice, a hinged cover, or a snap-on cover, would be supplied to cover this opening, to prevent the possibility of ends of work-sheets entering this opening, but the cover is omitted from the drawings. Even without a cover, the feeding-sheet is shielded from the work-sheets to a practical extent.

When the feeding-sheet 60 is in storage position, fully retracted, and bearing against the uprights 47, the extreme leading end of the feeding-sheet is held noticeably away from contact with the platen 3, and the feeding-sheet is preferably of such a length that the leading end is out of contact with any of the rear feed rollers 13. The extreme leading end may therefore be just in line with the gap provided between the forward edges of tables 40 and 42, as shown in Figure 10. If the extreme leading edge were in just slight contact with the feed rollers 13, rotation of the platen would still not draw the feeding-sheet from storage position, as the pull of the cord 51 is sufficient to resist any slight frictional pull on the leading end.

The typist may now press downwardly on the fingerpiece 49, which will partially rotate the rod 46, and thus cause the right-hand upright 47 to move away from the stop 48, and cause both uprights 47 to press against the feeding-sheet 60 at points where the feeding-sheet is reinforced by the clip 52, and thus slide the feeding-sheet downwardly forward through the chute. The 75

extreme leading end of the feeding-sheet will emerge through the gap between the tables 40 and 42, but is so guided by the parallel edges which form the gap, that it is bound to come in contact, first with one or more of the feed rollers 13, and then with either the platen 3, or with a work-sheet that may be in the typewriter. In any event, if the platen is rotated in normal line-space direction while the fingerpiece is so pressed, the pointed leading end will be quickly picked up and gripped in feeding engagement between the platen 3 and feed rollers 13. It will be understood that the two center rollers 13 engage the sheet 60 before the two end rollers 13, due to the use of the blunt point in the design of the sheet 60.

The pointed design of the feeding-sheet 60 tends to assure easy and accurate engagement, even though the feeding-sheet 60 may become worn from use. It will be understood that the matter of properly engaging the feeding-sheet is more difficult than that of engaging an ordinary work-sheet at the rear of the platen. The leading end of the feeding-sheet, as guided to engagement through the gap between the tables 40 and 42, does not come into contact with the platen 3 and feed rollers 13 at a natural and easy angle, as does a work-sheet guided by the upper surface of the paper-table 42. The engagement of the feeding-sheet 60 is more of a forced engagement. It is of course desired that when the feeding-sheet is properly gripped in engagement, that it be properly square, and accurately positioned with respect to other parts of the machine. If the leading end of the feeding-sheet were not pointed, it would be much more likely that one side of the feeding-sheet would engage before the other side, and thus tend to produce a crooked condition of the feeding-sheet. Using the pointed design, particularly since the cord 51 is so fastened as to exert its pull in the center of the feeding-sheet, in line with the point of the free end, tends to assure accurate and straight engagement. The side walls of the chute also tend to hold the feeding-sheet straight and square for engagement.

Once the feeding-sheet has become gripped between at least some of the feed rollers 13 and the platen 3, the typist may remove the finger from the fingerpiece 49, and the control rod, due to spring 50, will return to its original position. If the typist continues to rotate the platen in normal line-space direction, the feeding-sheet 60 will advance to the full operative position shown in Figures 4, 7 and 12. The feeding-sheet has now been fed almost entirely out of the chute.

Additional rotation of the platen 3 will not cause further advance of the feeding-sheet. This is prevented in one manner by the cord 51 being all paid out from the spool 54, and is prevented in another manner because the gap between the forward edges of the tables 40 and 42 is not large enough to permit the clip 52 to pass through. Furthermore, the openings 62 and 63 are now registered over the areas of pressure contact existing between the two series of feed rollers 12 and 13 and the platen. The feeding-sheet is therefore not being positively gripped by the pressure rollers 12 and 13. The feeding-sheet will stay in the operative position shown in Figure 4 as long as the platen 3 is not turned in backward direction, providing however, that the paper-release lever 16 is not operated to cast off the feed rollers 12 and 13.

If the feed rollers 12 and 13 are cast off, the

6 feeding-sheet will immediately tend to slide back into its shielded storage position in the chute. There is some friction resisting sliding movement of the sheet 60, but moderate strength of the spring 57 is enough to overcome friction, so whenever the control 16 is used to cast off the feed rollers 12 and 13, the feeding-sheet will automatically be retracted to inoperative position. If the spring 57 is sufficiently strong in its action, it will even retract the feeding-sheet when the feed rollers 12 and 13 are normally engaged; that is, the platen will be rotated in spite of the inherent friction of the platen and in spite of the effect of the ratchet-roller assembly 8. Such strength of spring 57 is not ordinarily desirable but can be used for certain specific applications.

It should be noted that when the feeding-sheet 60 is in the operative position, the pull developed by the spring 57, and through the cord 51 applied to the feeding-sheet, is sufficient in itself to prevent further advance of the feeding-sheet. It is not strictly necessary, when openings 62 and 63 are provided in the feeding-sheet, that the cord 51 be of such restricted length as to prevent the feeding-sheet 60 from feeding entirely out of the chute.

When the feeding-sheet 60 has been advanced to operative position as above described, it is properly located that work-sheets may be introduced. The leading end of the feeding-sheet projects upwardly, and is located forward of the carbon ribbons 70, but to the rear of the shield 35.

Figure 7 illustrates the feeding-sheet in useful position and shows three individual work-sheets as having been properly introduced for front feeding. The sheet 76 is disposed between the two carbon ribbons 70. By turning the platen in counter-line-space direction, the feeding-sheet 60 and all the work-sheets 76, 77 and 78 will immediately start moving in unison with the platen to lead the ends of the work-sheets to actual gripped feeding engagement. While the feed rollers 12 and 13 are registered with the openings 62 and 63 at the very beginning of backward rotation of the platen 3, the pull of the cord 51 assures immediate movement of the feeding-sheet 60 in unison with the platen 3. Friction alone, would tend to cause the feeding sheet to move into full gripped engagement with the platen, but the uniform pull of the cord 51 assures the most positive and reliable engagement.

The work-sheets 76, 77 and 78 are likewise not positively gripped by the feed rollers 12 and 13 at the very beginning of platen rotation, but are efficiently driven by friction. The use of the carbon ribbons 70 for manifolding tends to introduce a friction on the work-sheets, but not sufficient to prevent the work-sheets being positively and accurately drawn into full feeding engagement.

As the platen is turned backward, the leading ends of the sheets 76, 77 and 78 will emerge at the rear of the platen. The ejecting ends of these sheets will not enter the gap between the tables 40 and 42, but will be deflected up the incline of the table 40. Sufficient backward rotation of the platen will obviously cause ejection of the feeding-sheet 60 from the grip of the rear feed rollers 13, after which the action of the spring 57 will cause the feeding-sheet to move the slight further distance to fully retracted position. The front-feeding operation is now complete.

In Figures 10, 11, 12 and 13, the operation of my invention is shown, under the condition where a work-sheet is already in the machine when the front-feed operation is started. Fig-

ure 10 shows the condition before the start of the operation. Figure 11 shows the condition when the fingerpiece 49 is being pressed, which, particularly with the help of slight initial rotation of the platen, deposits the leading edge of the feeding-sheet in position for engagement, as shown in the Figure 11. By advancing the feeding-sheet to this engaging position, it is in contact not only with the feed rollers 13 but with one surface of the work-sheet 75. This condition is true only at the pointed center portion of the feeding-sheet and the side portions of the sheet are not yet in contact with either the rollers 13 or the sheet 75.

Figure 12 shows the condition after the platen has been rotated in line-space direction as indicated by the arrows. Figure 12 also shows the roll of paper from which the work-sheet 75 is feeding. The sheet 75 has been advanced a considerable distance by the platen rotation. The work-sheet 75 can be advanced to whatever extent desired after the feeding-sheet 60 has reached the limit of its advance, as the feed rollers 12 and 13 are engaged through the openings 62 and 63, and the platen 3 can be rotated further in line-space direction almost as freely as though the feeding-sheet 60 were not in operative position.

The paper-bail 29 has been preferably moved 30 to the extended position to better facilitate the introduction of the original work-sheet 78, which is set between the leading end of the feeding-sheet 60 and the uncoated side of the carbon ribbon 70. The platen is then turned in counter-line-space direction, which will turn the work-sheets 75 and 78 to proper position to receive the first line of typing, and this operation also serves to return the feeding-sheet 60 to the inoperative position.

Figure 13 shows the relationship when the platen has been thus turned in the direction of the arrows. It should be noted that the portion of the original work-sheet 78 which protrudes from the rear of the platen is positioned above 45 the surface of the table 40, and from a practical standpoint can not become located between the tables 40 and 42, as the natural direction in which the leading edge of the work-sheet 78 is ejected is above the table 40. When the necessary typing 50 has been completed, the platen is turned forward to eject the sheet 78 at the front of the platen, and a portion of the continuous work-sheet 75 may, if desired, be sheared off on the knife-like edge of the bail 29.

It is not strictly necessary to provide both an upper (regular) paper-table, and an under-table, to incorporate many of the features of my invention. Figure 14 illustrates a modification of my invention, in which only a single table 43 is provided, and the same control accessories are attached to the table 43 as are attached to the under-table 42 shown in the other drawings. In this modified design, the feeding-sheet 60 rests exposed on the inclined surface of the table 43, and this is obviously not as neat and efficient as where the feeding-sheet is shielded in a separate position. However, the operation in general is the same as with the preferred design shown in the other drawings.

70 A chief defect of the modified design is that under the condition of turning work-sheets nearly out of the typewriter in forward direction, and then turning them backward, the leading ends or edges of work-sheets may easily tend 75 to tangle and foul against the leading end of

the feeding-sheet 60, particularly if the edge of the sheet 60 becomes irregular from wear. The fact that the leading end of the sheet 60 is pointed, greatly lessens the number of times that work-sheets will jam with sheet 60, but the condition is troublesome. Also, such a backward-leading end of a work-sheet can tangle or foul with the rear edges of the openings 62 and 63. In addition, one or more of the work-sheets may become positioned wrongly at the underside of the feeding-sheet. This condition is shown by the dotted line 76 in Figure 14, and this position is undesirable, not only because the work-sheet 76 can easily jam with the edges of the openings 62 and 63, but will, if turned backward far enough, jam against the uprights 47. It should be noted that the providing of a shielded position for the feeding-sheet 60 is not fully effective in preventing fouling with the work-sheets unless the work-sheets are effectively prevented from following the feeding-sheet to the shielded position.

In the preferred design as shown in the drawings other than Figure 14, the feeding-sheet 60 in emerging from the chute or in sliding back into the chute, is forced to follow a curving path. This particular curve is effective from the point where the feeding-sheet leaves the gap between the tables 40 and 42, to the point where the feeding-sheet is engaged by the full pressure of the rollers 13. This curving path is well illustrated in Figure 12. This twist in the path does not interfere greatly with the smooth engagement of the leading end of the feeding-sheet during the process of engaging the feeding-sheet, since the feed rollers 13 are preferably turning in the direction of the arrow in Figure 11 as the leading end is pressed toward engagement.

This twist in the path of the feeding-sheet does cause friction of the feeding-sheet against one or both of the tables 40 and 42, and particularly against the lower forward edge of the table 40, and during the process of transferring the feeding-sheet to inoperative position this friction produces a tendency for the feeding-sheet to buckle, or bulge out in the area of curvature, instead of sliding through the gap. However, the action of the spring 57, exerting a constant pull on the end of the feeding-sheet that is within the chute, satisfactorily keeps the feeding-sheet taut and prevents the bulge from causing actual operating difficulty.

During the process of transferring the feeding-sheet to inoperative position, there would also be a tendency for the forward edges of the openings 62 and 63 to jam against the lower forward edge of the table 40. This tendency is eliminated by arranging the openings in the shape of a blunt point, as clearly shown in Figure 5.

Although I have described in detail a machine embodying my invention, it is to be understood that many modifications may be made without departing from the spirit or scope of the invention, and I am therefore not to be limited to the construction shown and described except as defined in the claims.

What is claimed is:

1. A front-strike typewriting machine having a rotatable platen, feed-roller means engaged along a rear portion of the platen, a paper-supporting table inclining rearwardly upward from the rear of the platen and having a front edge extending closely along said feed-roller means to

deflect a rearwardly ejected end of a writing sheet up and over the paper-supporting table, a feeding-sheet for front-feeding of work-sheets, which in inoperative position is located underneath the paper-supporting table and slidably supported thereunder, means to guide the leading end of the feeding-sheet to position to be engaged by the platen and feed roller means, control means to slide said feeding-sheet from inoperative position to engaging position whereby upon platen rotation a substantial portion of the feeding-sheet is fed out from under said paper-supporting table as the leading end is advanced to operative position, there being a curvature in the portion of the feeding-sheet located between said front edge and the area of maximum pressure by said feed-roller means, and resilient means at all times pulling said feeding-sheet toward inoperative position, to overcome buckling due to said curvature, as the feeding-sheet is pushed toward inoperative position by platen rotation.

2. The combination with a front-strike typewriting machine having a rotatable platen, a plurality of feed rollers therefor disposed along under and rear portions of said platen, and a paper-table inclining rearwardly upward from the back of said platen with an edge thereof located close to and parallel with the platen; of a feeding-sheet for use when front-feeding work-sheets to said machine, said feeding-sheet shiftable lengthwise of itself from an inoperative position underneath said paper-table to an operative position part-way around the platen, said feeding-sheet in moving back to inoperative position rubbing frictionally against the said edge of the paper-table, said feeding-sheet having openings therein which register with said feed rollers when the feeding-sheet is in operative position to permit engagement of the feed-rollers with the platen through said openings, said openings being pointed in the direction of the length of said feeding-sheet to prevent the edges of said openings from catching against said edge of the paper-table.

3. Means to operate a feeding-sheet to lead in a work-sheet in a front-strike typewriter, said typewriter having a rotatable platen, feed rollers therefor, and a paper-table inclined rearwardly upward from the back of said platen, said means including a chute located underneath said paper-table with the feeding-sheet slidable in the chute, yielding means connected to said feeding-sheet urging it fully into the chute, and manually actuatable control means to slide said feeding-sheet forward in said chute to eject the leading end thereof toward feeding engagement by the platen and feed rollers, said feeding-sheet having openings therein disposed to register with said feed rollers when the feeding-sheet has been advanced to operative position, to permit free rotation of the platen in line-space direction without further advancing said feeding-sheet.

4. The combination with a front-strike typewriting machine having a rotatable platen, a feed roller to cooperate therewith, an inclined paper-supporting table located rearwardly of said platen to direct a work-sheet to feeding engagement with the platen and cooperating feed roller; of a flexible feeding-sheet adapted to lead a work-sheet into said machine from the front side of said platen, said feeding-sheet when in inoperative position being located adjacent said paper-supporting table, a control member operable to cause said feeding-sheet, upon platen rotation in

forward direction, to be engaged by the platen and cooperating feed roller and shifted to operative position with the leading end of the feeding-sheet adjacent the front of the platen for front-insertion of a work-sheet, said feeding-sheet being shifted to inoperative position upon reverse rotation of the platen, and means preventing inadvertent re-engagement of said feeding-sheet by the platen and feed roller when the platen is rotated in either direction.

5. The combination with a front-strike typewriting machine, having a cylindrical platen, a feed roller engaged with an underneath portion of said platen, and an inclined paper-table located rearwardly of said platen; of a flexible feeding-sheet for front-introduction of a work-sheet in said machine, said feeding-sheet when in operative position being part-way around the platen and engaged by the platen and feed roller with the leading end of the feeding-sheet in front of the platen to receive a work-sheet, said feeding-sheet being ejected from engagement when the platen is turned to feed-in the work-sheet, with the leading end of the feeding-sheet then adjacent said paper-table, means to automatically shift said ejected feeding-sheet a distance away from engagement to inoperative position, and a control device to shift the leading end away from inoperative position and toward the platen and feed roller for re-engagement.

6. A front-strike typewriting machine including a platen, a feed roller to cooperate therewith, an inclined paper-table located to the rear of said platen, a flexible feeding-sheet which in inoperative position is located to the rear of the platen adjacent the paper-table, control means operable to cause engagement of the feeding-sheet by the platen and feed roller when the platen is turned, the leading end of the feeding-sheet being fed to the front side of the platen by continued turning of the platen, and means acting on the feeding-sheet to limit the distance that said feeding-sheet is advanced by platen rotation.

7. A front-strike typewriting machine having a rotatable platen, a feed roller engaged along the rear under side of said platen, types coactive with the platen along the front thereof, an upwardly inclined paper-guide in back of said platen to provide a path of support for extending portions of work-sheets, a flexible feeding-sheet to lead in a work-sheet introduced at the front of the platen, means on said machine to maintain the feeding-sheet in an inoperative position in back of said platen, control means on said machine operable to shift the feeding-sheet to engagement with the platen and feed roller to move said feeding-sheet partly around the platen to operative position, the feeding-sheet in leaving the platen toward inoperative position, following a distinctly separate path than the path of support for portions of work-sheets extending from the under side of said platen, said inclined paper-guide including means to prevent the ends of work-sheets from entering the path of the feeding-sheet.

8. The combination with a front-strike typewriter having a platen, feed-roller means engaged along the rear of the platen, a paper-table inclining rearwardly upward from said feed-roller means, the relationship of said platen, feed-roller means and paper-table being that the leading end of a front-introduced work-sheet will be directed up and over said table; of a flexible feeding-sheet to lead in work-sheets introduced at

the front of said platen, a storage compartment therefor located underneath said paper-table and adapted to partially enclose the feeding-sheet to shield the free end thereof from jamming with an end of a work-sheet ejected rearwardly from the under side of the platen, means mounted on said machine to hold the feeding-sheet in an inoperative position in said storage compartment, said feeding-sheet then being held out of inadvertent engagement with the platen and feed-roller means, said feeding-sheet being adapted to be engaged by the platen and feed roller means, and means to limit the distance said feeding-sheet can be fed by platen rotation 15 when so engaged.

9. The combination with a front-strike typewriting machine having a rotatable platen and a feed roller engaged therewith to produce a pressure area to feed a work-sheet; of a feeding-sheet to lead in a work-sheet from the front of the platen, the feeding-sheet when in inoperative position being located in back of said platen, said feeding sheet being shiftable from inoperative position to engaging position whereby upon platen rotation in line-space direction the feeding-sheet will be advanced part-way around the platen to operative position with the leading end to the front of said platen, said feeding-sheet having an opening therein which is then registered over the said pressure area permitting engagement of said feed roller with the platen through said opening, and means to hold said feeding-sheet against further movement when the platen is further rotated in line-space direction.

10. In a front-strike typewriting machine, a rotatable platen, a plurality of spaced-apart feed rollers engaged with the platen to feed a work-sheet, a paper-table inclining rearwardly upward from the back of the platen, a feeding-sheet for front-feeding work-sheets into the typewriter, a chute underneath said paper-table to support said feeding-sheet underneath said table, resilient means acting on said feeding-sheet to hold the feeding-sheet from inadvertent engagement by said platen and feed rollers, a control member actuatable to shift the feeding-sheet to position for engagement by the platen and feed rollers upon rotation of the platen whereby the 45 leading end of the feeding-sheet may be disposed at the front of the platen, said feeding-sheet having openings therein of such size and so distributed as to come in register with said feed rollers, said resilient means then tending to 50 prevent further movement of the feeding-sheet when the platen is turned an additional distance.

11. A front-strike typewriting machine having a rotatable paper-feeding platen, feed-roller means engaged therewith along a substantial lengthwise rear portion of said platen to feed a work sheet, a flexible feeding-sheet equal in width to a substantial portion of the platen length, said feeding-sheet when it is in inoperative position being located in back of said platen, means to 60 hold said feeding-sheet away from being engaged by the cooperative action of said platen and feed-roller means, means to shift said feeding-sheet to engagement by the platen and feed-roller means upon rotation of the platen, to feed 65 said feeding-sheet part-way around said platen for inserting a work-sheet by means of said feeding-sheet, the leading end of said feeding-sheet being pointed whereby the center portion of said leading end will contact said feed-roller means before side portions of said leading end.

12. The combination with a front-strike type-writing machine having a rotatable platen and a cooperating feed roller to feed work-sheets into said machine; of a flexible feeding-sheet adapted to lead a work sheet into said machine, said feeding-sheet having an inoperative position in back of said platen, a control element on said machine and having a fingerpiece associated therewith, operable to shift said feeding-sheet from said inoperative position toward the platen for engagement by the platen and feed roller upon rotation of the platen, resilient means mounted on said machine and connected to said feeding-sheet urging said feeding-sheet to be retracted to said inoperative position, a stop element to stop the movement of the feeding-sheet on reaching the inoperative position, and a stop means to limit the position to which the feeding-sheet may be advanced by platen rotation.

13. A front-strike typewriting machine including a cylindrical platen, a feed roller to cooperate therewith, an inclined paper-table extending rearwardly upward from the platen a guideway mounted on said machine adjacent said paper-table, a flexible feeding-sheet slidably positioned in said guideway and being guided widthwise and thicknesswise of itself by said guideway whereby when the feeding-sheet is slid downwardly forward the leading end will meet the platen and feed roller for engagement and by platen rotation will be gripped and advanced to the front of the platen to receive a work-sheet, means on said machine to maintain said feeding-sheet at a predetermined inoperative position in said guideway and free of inadvertent

engagement with said platen and feed roller, a control member on said machine, and a fingerpiece for operating said control member, to shift said feeding-sheet along said guideway to engagement with the platen and feed roller.

14. The combination with a front-strike type-writing machine having a rotatable platen, a feed roller acting on the under side of said platen to grip work-sheets, typing instrumentalities coactive with the platen at a writing line located along the front of said platen, and line-spacing mechanism for feeding the work-sheets upward past the writing line; of an upwardly inclined paper-table in back of said platen, a separate table located underneath said paper-table, a flexible feeding-sheet between said tables and supported on said separate table, a spring mounted on said machine and connected to said feeding-sheet urging said feeding-sheet to a predetermined inoperative position between the two said tables with the leading end free of engagement with the platen and feed roller, said paper-table arranged to deflect the bottom ends of work sheets above said paper-table and thereby shield the leading end of the feeding-sheet from being fouled by the bottom ends of work-sheets at any time the work-sheets are turned in counter-line-spacing direction while the feeding-sheet is in inoperative position, means on said machine to shift said feeding-sheet from inoperative position toward the feed roller so as to engage and advance the feeding-sheet when the platen is rotating, and means to limit the distance the feeding-sheet may be advanced.

WILLIAM E. McFARLAND.
